UNITED STATES PATENT OFFICE.

P. WILMER STEVENS, OF IRVINGTON, NEW JERSEY, ASSIGNOR TO REI-ENGINEERING CO., OF NEWARK, NEW JERSEY, A CORPORATION OF NEW JERSEY.

OIL BURNER.

Application filed January 24, 1927. Serial No. 163,025.

This invention relates to oil burners, and is intended more particularly for use in connection with house heaters or boilers, although it is to be understood that the invention is not confined to any particular use for which it may be found desirable or advantageous. It can also be employed with any kind of fuel other than oil, that being mentioned for brevity and without any purpose to limit the invention to use of one type of fuel.

The objects of the invention are to provide a burner which will obtain complete combustion of the fuel; to prevent deposit of soot or carbon; to secure proper mixture of the combustible ingredients; to provide means for sucking the oil to the burner; to avoid gravity feed to the burner; to prevent carbonization of the fuel in the feed pipe; to insulate the fuel feed pipe within the combustion chamber; to utilize steam pressure generated by the burner for feeding the fuel to the burner; to obtain a constant level feed for water for creating said steam; to provide for constant pressure of steam; to provide means for starting the burner in operation; to utilize said starting means for supplying air to the fuel during operation of the burner; to avoid undue noise in operation; to avoid noisy movable parts such as blowers; to utilize standard parts and fittings; to require minimum specially made parts; to secure throughout simplicity of construction and operation, and to obtain other advantages and results as may be brought out by the following description.

Referring to the accompanying drawings, in which like numerals of reference indicate the same parts throughout the several views,

Figure 1 is a perspective view of my invention shown in position in an ordinary type of house furnace, parts of the furnace being broken away to disclose the parts of the invention therein;

Figure 2 is a side elevation of the invention looking at the same from the further side as viewed in Figure 1;

Figures 3 and 4 are central vertical sectional views of the fuel and water float controls respectively, and

Figure 5 is a central vertical section of the burner chamber and fuel ejector.

In the specific embodiment of the invention illustrated in said drawings, the reference numeral 1 indicates a house-heating

furnace which may be of any usual construction providing a fire chamber 2. I have shown the grate covered with slag 3 or other suitable material to prevent damage to the grate and confine the heat within the fire chamber, but this may be varied as found desirable or necessary. The fire chamber has the usual door opening 4, shown as being closed by a door 5 having an appropriate hole 6 therein for viewing the interior and also for reaching to light the burner or for other purposes. In the specific construction disclosed, said door 5 is not intended to be opened after the burner is once installed, and forms not only a closure for the opening 60 but a support for the various parts constituting elements of my invention. 65

Within the furnace, and supported from said door 5, is a burner pot 7, and outside the furnace are float controls 8 and 9, the one control 8 providing a constant level of liquid fuel to be fed to the pot, and the other control 9 providing a constant level of water to be fed to the pot. The pot 7 is illustrated as a casting having upwardly 70 and outwardly flaring side walls with a flange 10 at the top receiving a cover 11 bolted or otherwise secured thereto for obtaining a steam-tight chamber 12 within said pot 7. At the bottom of this pot, the side walls turn inwardly and then upwardly within the pot, as at 13 in Figure 5, converging inwardly upward to form a re-entrant tapered portion at the middle of the pot. By this construction the lower portion 75 of the interior chamber 12 of the pot is an annulus, and it is within this portion that the level of water is maintained from which steam is created. 80

In a threaded opening in the top of the said re-entrant portion of the pot is mounted the outer member 14 of an ejector 15 through which steam generated in the pot finds exit and sucks fuel from the fuel float control 8 heretofore mentioned. The specific ejector illustrated is constructed with the said outer member 14 centrally and longitudinally recessed and having a contracted neck or venturi 16 near its lower end and a threaded opening alined therewith at the other end. The inner ejector member 17 is adjustably screwed into said threaded opening of the outer member, and provides a nozzle 18 which may be brought into proper relation to the Venturi contraction to form 90 95 100 105 110

an annular passage therewith, as clearly shown in Figure 5. The outer ejector member 14 is provided with a lateral threaded opening for receiving the end of the fuel feed pipe 19, there being a fuel passage from said pipe to the Venturi opening, and thus as a flow of steam under pressure or other actuating medium passes through the central passage 20 of the inner ejector member, a suction is created in the passage outside of the inner member sufficient to suck fuel through the pipe 19. Consequently a supply of fuel will be ejected with the actuating medium from the Venturi passage of the outer member into the tapered recess at the bottom of the pot. The fuel thus ejected, having been ignited, results in a jet of flame directed toward the grate of the furnace, the flame in practice spreading and curling upwardly outward along the walls of the combustion chamber of the furnace. It may be here noted that the inner member 17 of the ejector projects upwardly above the outer member 14 to a position terminating within the dome or crown of the cover 11 of the pot, see Figure 5, so that its central passage 20 opens into the pot as high in said pot as possible, which, combined with the draining effect of the dome or crown shape of the cover 11 upon moisture, obtains substantially dry steam as the actuating medium of the specific disclosure herein.

The fuel feed pipe 19 to the ejector passes out of the pot laterally through an appropriate opening, and outwardly through the furnace door 5 and is connected to the bottom of the float control 8, see Figures 1 and 2. The piping is preferably such that the level of the fuel in the float control is always lower than the said fuel feed pipe 19 to the ejector, or otherwise arranged so the fuel cannot gravitate to the ejector. This is an important feature of the invention, as from a safety consideration it is important not to permit flow of the fuel into the furnace when the ejector is not working. The ejector is adapted and arranged to elevate the fuel from the float control 8 and positively obtain flow thereof. The specific piping shown comprises a shut-off valve 21 at the outer end of fuel feed pipe 19, with other piping connecting said valve to the float control, including a vertical reach of pipe 22 or its equivalent up which the fuel must be raised by positive actuation other than gravity.

As heretofore indicated, float control 9 ensures a constant water level in the pot 7, there being a pipe 23 provided connecting the bottom of said float control with a lower part of the pot. As shown, said pipe 23 is threaded into an opening therefor in the outside wall of the pot adjacent the lower part thereof toward the door 5, said pipe extending outwardly through an appropri-

ate opening provided in said door to the exterior of the furnace. Preferably this line of piping from the pot to the water float control 9 includes a check valve 24, see Figure 1, which will allow flow of the water from the float control to the pot, but will prevent flow in the opposite direction. There is also provided means for equalizing the pressure in the upper parts of the pot and water float control 9 so as to obtain a replacement of water in the pot by gravity regardless of the pressure of steam or other medium in the pot. I obtain this equalization of pressure by a steam pipe connection 25 from the upper part of the pot to the upper part of the water float control. I have shown this pipe connection 25 as providing a length of pipe 26 screwed into the same opening 27 in the pot through which the oil or fuel pipe 19 passes from within the pot, Figure 5, said fuel pipe being shown as within said steam pipe. Outside of the furnace door, Figure 1, the steam pipe is provided with a T connection 28 with the oil pipe passing out of the straight-way end of the connection through an appropriate stuffing-box 29. A nipple connection or length of pipe 30 from the angular connection of the T also screws into the upper portion of water float control 9, thus obtaining a steam passage from the pot to the water float control. By this construction, the pressure in both places will be substantially the same and the water will therefore flow by gravity from the float control to the pot to maintain the level in the pot. It may here be noted that sudden building up of pressure in the pot would have a tendency to force the water from the pot into the float chamber until equalization of the pressures took effect, and it is to prevent such surging that I have provided the hereinbefore mentioned check valve 24 in the water pipe connection between the pot and water float control.

Particular attention is called to the construction above described whereby the fuel pipe 19 within the furnace is enclosed by the steam pipe 25, which affords a protection for the fuel pipe against excess heat which would tend to carbonize the fuel. The steam within the pipe surrounding the fuel pipe not only provides a substantially uniform temperature for the fuel pipe, and also acts to pre-heat the fuel before mixture with the steam and before it is ejected into the combustion chamber. This preheating and maintaining at a constant but not excessive temperature are believed to be important features of the invention and essential to proper operation of the device. Further protection of the fuel pipe 19 from excessive heat is obtained by surrounding the steam pipe 25 which encloses it with another pipe or casing which opens to the atmosphere

through the door so as to surround the steam pipe with an air space in which the air may circulate. In carrying out this feature the pot is provided with an enlarged 5 boss 31 around the screw-threaded opening for the steam pipe 25, see Figure 5, said boss being hollowed and screw-threaded to receive a pipe 32 which is sufficiently larger than the steam pipe which it surrounds to 10 provide an adequate air space. It is to be noted, however, that there is no opening through the wall of the pot for air from this air casing or pipe 32, the said wall of the pot forming an end closure for said casing. The forward end of said casing or 15 pipe 32 is screw-threaded and receives one nut 33 immediately inside the furnace door 5 and another nut 34 immediately outside the said door, see Figure 1, thereby holding 20 the pipe or casing in position with its end open to the atmosphere, and also providing an adequate mounting for the support of the pot from the door.

Within the annular lower portion of the 25 material forming the pot, in the part thereof where the outer walls are directed inwardly and turn upwardly to form the inner walls, is an annular passage 35, Figure 5. This opening or passage 35 has a lateral 30 opening for connection to a gas pipe 36 which extends outwardly through the door of the furnace. The outer end of this gas pipe 36 is shown flared in Figures 1 and 2, and provided with air-intake openings 37 35 and gas service connection jet 38. The bottom of the pot is pierced with a plurality of burner holes 39 into the annular passage 35, so that when gas is supplied through jet 38 and pipe 36 to said passage, it may escape 40 through said burner holes and be ignited for heating the water in the pot to a boiling temperature to obtain necessary steam pressure for starting operation of the device. After the steam pressure is obtained so the 45 fuel is ejected and becomes ignited, sufficient heat is generated thereby to maintain the steam pressure within the pot, and then the gas is shut off by a suitable valve 40 beyond the jet. Air will continue to be sucked in 50 through the air-intake openings 37 of the gas supply pipe and will pass out into the combustion chamber through burner holes 39, mixing with the ejected fuel to supply pre-heated air for obtaining proper and 55 complete combustion.

For economy and convenience in manufacture, I prefer to construct both the oil and water float controls 8 and 9 as nearly alike as possible. Each comprises a bowl-like casting 41 in the present showing, each having a lateral chamber extension 42 from the bowl part. Within each bowl is shown a ball float 43 having a lateral stem 44 comprising a first-class lever pivoted, as at 45, near the end of said stem or lever furthest

from the ball so as to provide a long lever arm between the pivot and the ball and a short lever arm on the other side of the pivot. The short lever arm carries a floating plunger valve 46 which depends into a valve 70 seat 47 screw-threaded into the bottom of the extension of the valve chamber. Lifting of the ball will accordingly depress the valve stem and cause the valve to seat. Entry of the fuel or water, as the case may be, is 75 through the valve seat, herein shown as formed in the upper end of a valve coupling directly connected to the supply pipe. Obviously as the fluid level lowers in the float chamber, the lever connected with the ball 80 raises the valve and admits more fluid until the ball rises sufficiently to swing the lever and again close the valve. Each valve chamber is provided with a cover 48, and in case of the water control 9, since steam pressure 85 is admitted therein, the cover is properly secured and packed to prevent leakage of the steam. In the case of the fuel control 8, an appropriate aperture 49 is provided in the cover to maintain atmospheric pressure 90 within the chamber.

It is desirable and probably necessary to proper operation of the device, to maintain as nearly as possible a constant pressure of steam within the pot and water float chamber, as well as to prevent the pressure from building up unduly or to dangerous amounts. I accordingly provide a suitable steam release valve 50 in that part of the system, the same being shown herein as carried by 95 the cover 48 of the water float control 9. It is within the scope of the invention, however, to position this relief valve elsewhere so long as it will function to release the steam pressure as necessary, and thereby obtain an automatic regulation of the steam pressure. While the construction of the valve itself may vary without affecting the underlying principle, I have illustrated for purposes of being definite, a plunger valve 100 head 51 held against its seat by a coil spring 52 the tension of which may be adjusted by manipulating a retaining nut 53 threaded on a central stud or post 54 upon which said plunger valve head is slidable. An inverted 105 cup-like cover may also be carried by said post and depend over the spring and valve head for protecting said parts if so desired, said cover being free from the valve head so as to permit free passage of the escaping 110 steam to the atmosphere.

Various modifications and changes in structural details may be made in manufacturing my improved burner, by those skilled in the art, without departing from the spirit and scope of the invention, and therefore I do not desire to be understood as limiting myself except as required by the following claims when construed in the light of the prior art.

Having thus described the invention, what I claim is:

1. An oil burner comprising a pot having a chamber for producing steam pressure, an ejector mounted and enclosed within said chamber with one end opening thereinto for receiving steam pressure and the other end opening outside of the pot, and means for supplying oil to said ejector.
- 10 2. An oil burner comprising a pot having a chamber for producing steam pressure, an ejector mounted and enclosed within said chamber with one end opening thereinto for receiving steam pressure and the other end 15 opening outside of the pot, and an oil pipe extending to said ejector through said pot.
- 20 3. An oil burner comprising a pot for having a chamber for producing steam pressure, an ejector mounted and enclosed within said chamber with one end receiving steam pressure and the other end opening outside said pot, and a float feed below the level of said ejector for supplying oil thereto.
- 25 4. An oil burner comprising a steam generating pot having a reentrant wall and a steam chamber, an ejector mounted and enclosed within and leading from the interior of said pot through its reentrant wall, means 30 for supplying water to said pot, and means for supplying oil to said ejector through said chamber.
- 35 5. An oil burner comprising a steam generating pot having a conical reentrant wall, an ejector mounted and enclosed within and leading from the interior of said pot through the apex of its reentrant wall, means for supplying water to said pot, and means for supplying oil to said ejector 40 through said chamber.
- 45 6. An oil burner comprising a steam generating pot having a reentrant wall and an annular passage adjacent said wall with exterior discharge openings, means for supplying air to said passage, an ejector leading from the interior of said pot through its wall, means for supplying water to said pot, and means for supplying oil to said ejector by suction.
7. An oil burner comprising a steam pot 50 having an ejector having a passage leading from the interior of the pot outside the same, means for supplying water to said steam pot including a float control, a pressure equalizing pipe leading from the steam pot to the 55 water feed float control, and an oil feed pipe passing through said steam pipe to the ejector.
8. An oil burner comprising a steam pot having an ejector having a passage leading 60 from the interior of the pot outside the same, means for supplying water to said steam pot including a float control, a pressure equalizing pipe leading from the steam pot to the water feed float control, and an 65 oil feed pipe entering the steam pot through said steam pipe and extending to the ejector.
9. An oil burner comprising a steam generating pot, an ejector leading from the interior of the pot through its wall, means for supplying water to the pot, means for supplying oil to the ejector, an annular passage adjacent said ejector and having discharge 70 openings directed away therefrom, and means for supplying air to said passage.
10. An oil burner comprising a steam generating pot, a burner nozzle leading from the interior of said pot through its walls, means for supplying water to said pot, means for supplying oil to said nozzle, a 75 substantially annular passage adjacent and coaxial with said nozzle with discharge openings directed away from said pot, and means for supplying air to said passage.
11. An oil burner comprising a steam generating pot having a reentrant wall and an annular passage adjacent said wall with discharge openings directed away from said wall, means for supplying air to said 80 passage, a burner nozzle leading from the interior of said pot through said wall, means for supplying water to said pot, and means for supplying oil to said burner nozzle.
12. The oil burner set forth in claim 10 with the addition of means for supplying 85 heating gas to said passage, and means for controlling said supply of gas.

P. WILMER STEVENS.
